TEXTILE PROCESSING MACHINE

Filed Sept. 7, 1929

UNITED STATES PATENT OFFICE

JAMES H. SKITT, OF PHILADELPHIA, PENNSYLVANIA, ASSIGNOR TO SMITH, DRUM & COMPANY, OF PHILADELPHIA, PENNSYLVANIA, A CORPORATION OF PENNSYLVANIA

TEXTILE PROCESSING MACHINE

Application filed September 7, 1929. Serial No. 390,992.

The present invention relates to textile machines and more particularly to the application of a liquid to textile material for dyeing, finishing, and other liquid treating operations.

Some of the objects of the present invention are to provide an improved machine for subjecting textile goods to a liquid treatment; to provide a more efficient and practical way of applying treating liquids to textile goods; to provide means for causing excess liquid to be directed against the material instead of falling directly into the main liquid tank; to provide means for applying liquid to textile material in the form of loops, skeins, hanks and other forms wherein uniform and equal distribution of the liquid takes place; to provide a device associated with a liquid applying means to vary the position of material being treated with respect to the applying means; to provide a material shifting device including means for directing liquid to the material; and to provide other improvements as will hereinafter appear.

In the accompanying drawings Fig. 1 represents a side elevation of a textile processing machine embodying one form of the present invention; Fig. 2 represents a section on line 2—2 of Fig. 1; and Fig. 3 represents a plan of the support and certain associated parts.

Referring to the drawings one form of the present invention consists of a tank 10 for holding a supply of liquid 11, such as dye, finishing solution, or any other treating liquid, and is preferably of open top construction to allow the material to enter the tank and hang suspended above the treating liquid. In the present instance and by way of example, the material shown is in the form of hanks of yarn 12 and may be of coarse material, such as wool or cotton, or of the finer grades of material, such as silk and rayons, all of which can be efficiently treated by means of the present invention.

For suspending the hanks 12 within the tank and with the lower ends thereof above the treating liquid 11, a tubular support 13 is mounted to extend transversely across the

open top of the tank 10 and is fixedly mounted at one end in a pair of brackets 14 which are secured to and supported by a rigid skeleton frame 15 mounted at one end of the tank 10. Each of the brackets 14 as here shown carries a set screw 16 threaded therethrough for engaging the tubular support 13 and anchoring it against relative movement. Thus the support 13 is held fast at the end which projects beyond the side of the tank 10 while the major portion thereof extends horizontally above the open top of the tank 10 in such a position that when the hanks 12 are placed thereon the lower ends will allow the excess treating liquid to return to the main supply. The hanks 12 can be freely placed on or removed from the support 13 since its outer end is unobstructed and therefore can be inserted through the loops of material to permit the latter to be properly placed. In connection with the free end of the support 13 it will be noted that it is closed by a stationary hub 17 having a flange 18 of greater diameter than the support 13 to thereby serve as a holding guide to prevent the hanks from improperly working off of the end of the support.

In order to deliver the treating liquid to that portion of the hanks which rests upon the support 13 so that the individual skeins of material are separated and uniformly saturated while the excess liquid can run down the skeins, the upper surface of the fixed support also provided with one or more rows of perforations 20, and the lower surface thereof also provided with one or more rows of perforations 21. In the preferred form of the invention there are four rows of perforations 20 lengthwise of the upper surface and three rows of perforations lengthwise of the lower surface, and the arrangement is such that the rows 20 discharge liquid directly against the material while the rows 21 indirectly deliver the liquid to the material. The fixed end of the support 13 is connected to and communicates with a pipe 22, here shown as vertically disposed and terminating at its lower end in a connection 23 with the discharge end of a pump 24. A valve 25 may be mounted upon the end of the pipe 22 for drain purposes as

will be understood. The pump 24 is driven from any suitable source of power and has an intake pipe 26 connected to the tank 10 at its bottom and communicating with the interior thereof, whereby the liquid can be withdrawn from the tank and circulated by way of the pipes to the support 13 and from whence it is discharged by way of the perforations 20 and 21.

10 For the purpose of changing the position of the hanks 12 with respect to the support 13 as occasion demands, a rotatable shifting means is provided consisting, in the present instance, of a rigid plate element 27 radially disposed with respect to the support 13 and extending substantially the length thereof. One end of this element 27 is connected to a plate 30 which is supported and journaled upon a bearing stud 31 which is threaded into 15 the hub 17 in coaxial relation with the support 13, while the other end of the element 27 is connected to a plate 32 formed as an integral extension of the hub 33 of a worm gear 34. This gear 34 is journaled for free rotation upon a sleeve 35 fixed to the support 13 and having a flange 36 which serves as a guide abutment for the hanks 12 at the opposite end of the support 13 from the flange 18. Motion is transmitted to the worm gear 34 by a worm 20 shaft 37 extending lengthwise of the machine and supported by bearing brackets 38 fastened to the frame 15. This shaft 37 can be arranged to operate as many supports 13 as are used upon the machine. A collar 40 is fixed 25 to the sleeve 35 by a set screw 41 to form with the flange 36 a channel in which the worm gear 34 travels. It will thus be seen that operation of the shaft 37 causes the element 27 to swing about the support 13 as an axis to thereby lift 30 one side of a loop of material to advance the loop relative to the support 13 so that another portion is brought into contact with the support for direct treatment.

For the purpose of deflecting the liquid discharged from the perforations 21, the element 27 is provided with a flange 42 positioned in close proximity to the support 13 and having the face 43 curved concentrically with the contour of the support 13. The spacing of 35 the flange 42 from the support 13 is such as to provide a relatively narrow clearance passage 44 through which the liquid can travel to discharge beyond the side edges of the flange. These edges are preferably spaced from the 40 suspended loops of material to allow excess liquid to drop to a lower level. This level is fixed by a plate flange 45 provided at the lower part of the element 27 and extends across the space between the sides of the material loops to contact therewith and maintain them separated while also at one side serving as a lifting means when the element 27 is rotated. It will thus be evident that the flange 45 is in 45 position to intercept any liquid dripping from the flange 42 and cause it to flow laterally

against the material and give a supplemental treatment by liquid which otherwise would return directly to the tank 10.

In the operation of the machine the hanks or other form of material are looped about 70 the support 13 so that the material is suspended within the tank 10. The pump 24 is now started and the treating liquid circulated by way of the intake pipe 26, pump 24, connection 28, pipe 22 and support 13 from whence it is discharged by way of the perforations 20 and 21, the former delivering the liquid directly against the material while the latter delivers it against the deflector flange 42. The pressure of the discharged liquid 75 issuing from the perforations 20 is such as to lift the skeins sufficiently to allow a film of the discharged liquid to flow between the hanks and the support 13 and into the individual strands of the yarn or other material as it is separated by the discharge pressure. Thus there is a continuous flow of treating liquid from the perforations which coacts with the separated strands of material to give 80 a uniform treatment throughout the body of the material. The liquid which is restricted in its flow through the perforations 21 by the face of the deflector flange 42 follows the clearance passage 44 and discharges laterally 85 against the side of the material which hangs adjacent thereto. This supplements the action of the liquid discharged from the perforations 20 by again opening up the skeins to admit the liquid for treatment thereof and since the skeins are hanging vertical the liquid will flow downward thereon toward the tank. Any liquid which drops directly downward from the sides of the deflector flange 42 will be caught by the separating and lifting flange 45 and since this is in contact with the 90 material it will divert this otherwise waste liquid to flow into and then downward of the skeins of material.

It will now be apparent that a complete 95 unitary processing machine has been devised for efficiently and economically treating skeins of cotton, wool, silk, rayon or any other material in any other form by the use of a perforated support for supporting material and having associated therewith a relatively 100 rotatable means for lifting the material at predetermined intervals to change its position upon the support. Furthermore a more even and uniform treating of the material 105 takes place due to the fact that provision is made for delivering the treating liquid to the material at several different places, each successive treatment supplementing that which has preceded. A higher percentage of the circulated liquid thus becomes effective for 110 treating purposes and reduces the amount which has to be recirculated.

While only a single form is shown in which this invention may be embodied, it is to be understood that the invention is not limited 115

to any specific construction, but might be applied to various forms without departing from the spirit of the invention or the scope of the appended claims.

5 Having thus described my invention, I claim:

1. A textile processing machine comprising the combination of a support arranged to suspend material to be treated, said material 10 directly contacting with said support, means to discharge a treating liquid upon said material, supplemental discharge means for liquid to treat said material intermediate of its length, and an element normally located 15 below said support and movable relative to said support for changing the position of said material relative to said support.

2. A textile processing machine comprising the combination of a support arranged 20 to suspend material to be treated, said support having perforations in the top portion thereof opening against the supported material and perforations in the bottom portion thereof opening into the space between suspended 25 portions of said material, a deflector mounted in juxtaposed relation to said bottom perforations to cause liquid to be discharged laterally against said material, means for introducing liquid into said support and an element movable relative to said support for changing the position of said material relative to said support.

3. A textile processing machine comprising the combination of a support arranged to 35 suspend material to be treated, said support having perforations in the top portion thereof opening against the supported material and perforations in the bottom portion thereof opening into the space between suspended 40 portions of said material, means for introducing liquid into said support, an element movable relative to said support for changing the position of said material relative to said support, and a deflector carried by said 45 element and normally opposed to said bottom perforations to cause liquid to be discharged laterally against said material.

4. A textile processing machine comprising the combination of a tubular support having 50 discharge outlets respectively at its top and bottom, a deflector arranged opposite said bottom outlets, means for introducing liquid into said support under pressure to discharge through said top outlets against material suspended on said support and through said bottom outlets against said deflector to be directed laterally against said material, and means movable relative to said support for changing the position of said material relative to said support.

5. A textile processing machine comprising the combination of a tubular support having 55 discharge outlets respectively at its top and bottom, a deflector arranged opposite said bottom outlets, and means for introduc-

ing liquid into said support under pressure to discharge through said top outlets against material suspended on said support and through said bottom outlets against said deflector to be directed laterally against said material.

6. A textile processing machine comprising the combination of a tubular support having discharge outlets therein, means for introducing liquid under pressure into said support to discharge through said outlets against material suspended upon said support, and a material lifting device arranged to be swung about said support to change the position of said material, said device having a part located to catch liquid dropping from said support and direct said liquid against said material.

7. A textile processing machine comprising the combination of a tank for treating liquid, a support for suspending material within said tank, said material directly contacting with said support means for directing treating liquid against said material between said support and material and against the suspended portion of said material, and means rotatable about said support for lifting said material to change the position thereof.

Signed at Philadelphia, county of Philadelphia, State of Pennsylvania, this 30th day of Aug., 1929.
